ENGINE STARTING MECHANISM

Romeo M. Nardone, Teaneck, N. J., assignor to Joseph J. Mascuch, Maplewood, N. J.

Application April 1, 1952, Serial No. 279,886

8 Claims. (Cl. 123—179)

This invention relates to internal combustion engines, and particularly to means for imparting initial rotary movement to the rotating parts of such an engine, to facilitate starting thereof; the combustion of fuel in the engine being promoted by such initial rotation by externally applied torque.

In engine starting mechanism as commonly employed heretofore, it has been customary to make the engine engaging elements in such form as to be self-disengaging under the impetus imparted to the engaged element of the engine by the first power impulses occurring in the combustion chambers of the engine. For this purpose the inter-engaging elements of the starter and engine have commonly been provided with an "over-running" or ratchet type of clutch tooth, or jaw, so that the first acceleration of the engine clutch element to a speed beyond that of the starter clutch element causes the starter clutch element to be pushed back to the disengaged position; the engine then continuing to run under its own power, without rotating the starter with it.

Offsetting the advantage of self-disengagement, however, is the disadvantage that an over-running type of clutch element can not readily be engaged, with good intercalation of the driving surfaces, under all conditions that may arise. For example, where the starting unit is of the turbo-rotor type, with the rotor being energized by application thereto of pressure fluid generated in a propellant, or "rocket" type of pressure generator, the tendency is toward rapid acceleration of the starter and this in turn means that the co-operating clutch elements of the starter and engine may fail to engage firmly; or they may do so only after the starter clutch element has attained relatively high speed. Moreover there may be premature disengagement, due to isolated firing impulses of insufficient regularity to produce sustained self-operation of the engine. In such instances a second attempt to engage the clutch elements is called for, but here again the re-engagement may prove even more difficult to accomplish successfully, because of the manner of forming the clutch teeth.

A feature of the present invention is the permanent coupling of the starter and engine clutch elements, thus eliminating all the hazards attendant upon use of disengaging clutch elements. With such permanent coupling the starter rotor assembly continues to rotate after the started engine becomes self-operative; and a second feature of the invention is the incorporation into the starter of automatic gear ratio changing means, functioning to convert the driving ratio from, say, 6 to 1 ratio that prevails during starting to a 1 to 1 ratio for subsequent operation.

A third feature of the invention is a novel fluid-pressure responsive mechanism for controlling the driving ratio between the starter rotor and the engine to be started.

A fourth feature of the invention is a fluid pressure operated engine starting mechanism involving a turbine rotor, an engine-engaging element, a reduction gear train

2

connecting the turbine rotor and engine-engaging element, a fluid receiving bellows assembly adapted to apply braking force to one element of said gear train, and means for supplying fluid under pressure to said rotor and bellows assembly, simultaneously, from a common supply manifold interposed between said rotor and bellows assembly.

These and other features of the invention will be understood upon reference to the following description of the preferred embodiment of the invention as illustrated in the accompanying drawings wherein:

Fig. 1 is a central sectional view of the portion of the mechanism lying on one side of the longitudinal axis; and

Fig. 2 is a sectional view along line 2—2 of Fig. 1.

In these drawings the rotor 5 is shown as secured to the flanged end of the central shaft 6, and the engine-engaging element 7 is shown as having a rearwardly extending shank 8 that is splined and pinned to the central hub 9 of an element having angularly spaced axles 10 carrying the several planet gears 11 (only one of which is actually shown in Fig. 1) which mesh constantly with the "sun" gear 12 of the planetary system; the said gear 12 being formed by cutting gear teeth about the periphery of central shaft 6, along the forward section of the shaft. Planets 11 also mesh constantly with the teeth of orbital gear 13, and are held in assembly therewith by retainer rings 14, 15 insertable in circular grooves cut in the inner periphery of orbital gear 13; the rings 14, 15 thus retaining the side plates 16, 17 respectively.

The central shaft and the planet carrier 10 are supported in the sectional, cylindrical housing 18, 19, 20 by ball bearing assemblies 21, 22 retained in place by flanges formed on the transversely disposed supporting walls 23 and 24, respectively. Additional ball bearing assemblies 26, 27 facilitate relative rotation between the shaft 6 and the planet carrier 10. A fifth ball bearing assembly 28 is interposed between the flange 29 of wall 24 and the plate 30 which carries the first series of turbine blades 31, disposed between the rotor blades 32 and the circular flange 33 in which are carried the fluid supply nozzles 34, shown best in Fig. 2. These nozzles 34 receive the pressure fluid from annular manifold 35, to which the fluid is delivered by a conduit (not shown) connecting with the fluid source (a "rocket motor" or other propellant unit, for example). The extending rim 36 of the plate 30 supports the third series of turbine blades 37 which receive the fluid after it passes through the rotor blades 32. The expanded and spent gases are exhausted out of the rear section of the housing, after emerging from the reaction blades 37.

The automatic ratio changing means above referred to includes two sets of annular brake rings 38, 39 and a speed responsive clutch plate 41 shiftable laterally to frictionally engage the plate 17 of the orbital gear assembly 13—15—17, and thereby cause rotation of the entire gear train as a single unit, provided there is no simultaneously acting force to compress the brake rings, one against the other. Such a force does act, however, during the engine starting phase of operation; the means for producing such force being shown as taking the form of a brake-applying pressure plate 46 having a series of angularly spaced pockets housing bellows assemblies 47 (one only being visible in Fig. 1) whose end plates 48, 49 react upon the pressure plate 46 and the transverse wall 24, respectively; the bellows plates 49 having central extension that screw into threaded sockets in said wall 24. The wall 24 and the bellows plates 48, 49 have registering passages serving to introduce into the interiors of the bellows a part of the supply of pressure fluid that is present in the manifold 35. The pressure thus exerted

upon the plate 46 is effective to cause application of braking force to the orbital gear 13; it being noted that the individual brake rings 38 are secured to the housing by splines 51, while the inter-leaving brake rings 39 are secured to the orbital gear by splines 52. Springs 40 urge the brake rings back into non-engaging positions immediately following exhaustion of the fluid pressure supply.

To trace through a cycle of operation, upon the introduction of gases under pressure into the manifold 35, these gases pass in two directions—to the left into the bellows units—to engage the brake and thereby lock the orbital gear 13 to the housing, and to the right, into the blades of the rotor 5, to rotate the shaft 6 at relatively high speed, and the engine-engaging element 7 at relatively low speed, due to the speed reducing effect of the planetary system. This rotation of the engine-engaging element is, of course, imparted to the moving parts of the engine with which the element 7 is connected, and thereby permits the engine to become self-propelling by reason of combustion of its own fuel in its combustion chambers.

As engine fuel combustion proceeds, the engine speed increases, and the starter elements 7, 8, 9 and 10 are accelerated correspondingly. This increase in speed produces a proportionate increase in the magnitude of the centrifugal force acting upon balls 54 in ball-race 55 of planet carrier 10. As the balls 54 move outward, radially, under the influence of this increasing centrifugal force, the clutch plate 41 is shifted to the right, and the resulting pressure upon orbital gear plate 17 causes the entire orbital gear assembly to begin to rotate in unison with the planet carrier 10; the brake elements 38, 39 being no longer effective to prevent such rotation, as the fluid pressure in the manifold 35, and bellows 47, has by this time dropped off to a negligibly small value, quite insufficient to hold the brake rings engaged, against the disengaging pressure of the springs 40. Hence the entire gear train of the starter mechanism, including the shaft 6 and rotor 5, becomes a single rotary unit, synchronized with the rotating parts of the engine it started; and because all parts move as a single, integrated unit, there is no danger of tooth breakage or other injury being inflicted by one of such parts upon another.

What I claim is:

1. In an engine starting mechanism, an engine-engaging element constantly in driving connection with a engine part, a turbine rotor in axial alignment with said engine-engaging element, means drivably connecting said rotor and element, said connecting means including a carrier, fixed to the said element a planetary gear train comprising planet gears rotatably mounted upon the carrier and driven by the rotor and an orbital gear surrounding said planet gears, said orbital gear being normally free to rotate with said planet gears about the common axis of rotation of said turbine rotor and engine-engaging element, and means responsive to admission of pressure fluid into said mechanism to both energize said rotor and simultaneously lock said orbital gear against rotation.

2. An engine starting mechanism as defined in claim 1, wherein said planetary gear train further includes a planet gear carrier, and centrifugal clutch means for drivably connecting said planet gear carrier with said orbital gear.

3. An engine starting mechanism as defined in claim 1, wherein said gear locking means includes a series of brake rings rotatable with said orbital gear, a second series of brake rings secured against rotation, and pressure fluid receiving means for causing said second series of brake rings to exert braking force upon said first named series of brake rings.

4. An engine starting mechanism as defined in claim 1, wherein said gear locking means includes a series of brake rings rotatable with said orbital gear, a second series of brake rings secured against rotation, and means including fluid receiving bellows assemblies for causing said second series of brake rings to exert braking force upon said first named series of brake rings.

5. In an engine starting mechanism as defined in claim 4, an annular fluid supply manifold adjacent said bellows assemblies, and means for establishing fluid flow therebetween.

6. An engine starting mechanism comprising, the combination of an engine-engaging member, a turbine rotor in axial alignment with said engine-engaging member, means drivably connecting said rotor and member, said connecting means consisting of a carrier fixed to the rotor of a planetary gear train comprising planet gears rotatably supported by the carrier and driven by the rotor, and an orbital gear being normally free to rotate with said planet gears about the common axis of rotation of said turbine rotor and engine-engaging member, a centrifugal clutch means carried by the planet gear carrier for drivably connecting said planet gear carrier with said orbital gear, and means responsive to admission of pressure fluid into said mechanism to both energize said rotor and simultaneously lock said orbital gear against rotation, whereby driving connection of the entire assembly, through the engine-engaging member, is constantly maintained.

30 7. An engine starting mechanism comprising, the combination of an engine-engaging member, a turbine rotor in axial alignment with said engine-engaging member, means drivably connecting said rotor and member, said connecting means consisting of a carrier a planetary gear 35 train rotatably mounted upon the carrier and driven by the rotor comprising planet gears, and an orbital gear being normally free to rotate with said planet gears about the common axis of rotation of said turbine rotor and engine-engaging member, a centrifugal clutch means comprising a plurality of balls disposed in a ball-race carried by the planet gear carrier for drivably connecting said planet gear carrier with said orbital gear, and means responsive to admission of pressure fluid into said mechanism to both energize said rotor and simultaneously lock 40 said orbital gear against rotation, whereby driving connection of the entire assembly, through the engine-engaging members, is constantly maintained.

8. An engine starting mechanism comprising the combination as defined in claim 1, wherein said gear locking 50 means consists of a series of brake rings rotatable with the orbital gear, a second series of brake rings secured against rotation, and pressure fluid receiving means for causing said second series of brake rings to exert braking force upon said first named series of rings.
